UNITED STATES PATENT OFFICE.

WILLIAM S. MENDEN, OF BROOKLYN, NEW YORK, ASSIGNOR TO MEGOSIN COMPANY, INC., A CORPORATION OF NEW YORK.

SYSTEM OF CONTROLLING RAILWAY-CARS.

1,209,468.

Specification of Letters Patent. Patented Dec. 19, 1916.

Application filed June 6, 1914. Serial No. 843,441.

To all whom it may concern:

Be it known that I, WILLIAM S. MENDEN, a citizen of the United States, and resident of the borough of Brooklyn, in the county of 5 Kings and State of New York, have invented certain new and useful Improvements in Systems of Controlling Railway-Cars, of which the following is a full and clear specification.

10 This invention relates to means for automatically controlling the operation of cars and has for its primary object to provide suitable instrumentalities and operating connections therefor, which upon becoming 15 active automatically, will continue in action until the car comes to rest, the normal conditions of control being automatically re-established as soon as the car is at rest. Preferably, such instrumentalities include 20 or are related to brake-applying means and means for successively interrupting and re-establishing the main operating circuit.

One of the objects of this invention is to provide improved emergency control apparatus for rapid transit cars which when set 25 in action completely eliminates the motorman as a controlling factor, until the car or train comes to rest, whereupon the control is automatically restored to the motorman. 30 Toward the attainment of this object the preferred means includes a circuit breaker in the main power circuit and a brake-applying instrumentality, both of which are subject to the emergency control apparatus.

35 Another object is to provide an improved unit system of control which will include motive power, brakes, maximum and minimum speed limits and an intermediate control, which when actuated automatically 40 renders the speed control inoperative and brings the car or train to rest by preventing the reestablishment of the motive power and release of brakes until the car is at rest.

45 Another object is to provide an improved automatic control which is different in principle of operation and effects produced from either the arbitrary control of a motorman in accelerating or retarding the vehicle, or the speed control devices by which maximum and minimum speed limits are maintained automatically.

Other and further objects will appear in the specification and be pointed out in the claims, reference being had to the accompanying drawings in which the invention is 55 exemplified.

In the drawings, Figure 1 is a diagrammatic view of the circuits on a single car showing one embodiment of my invention, certain of the instrumentalities to be hereinafter referred to being shown in section and others in elevation; Fig. 2 is a diagrammatic view of another embodiment.

In the embodiment shown in Fig. 1, a brake control valve 1 is connected to the 65 train pipe 2 on one side and is provided with an outlet pipe 3 on the other side, adapting it to discharge into the air thereby. Said valve is provided with a pressure chamber 4 which is in continuously open communication with an upper chamber 5 by means of a channel 6. A valve seat 7 is suitably arranged to be closed by a valve 8 which has a valve stem 9 slidably supported in the cap 10 of the valve. Interposed between the 75 valve 8 and the cap 10 is a spring 11 which coöperates with the air pressure in the chamber 5 to normally retain the valve 8 against the seat 7 when the vehicle is moving. A pipe 12 serves to connect the chamber 5 with 80 a chamber 13 of a housing 14, within which is mounted an electro-responsive device in the form of a magnetic coil 15 which when energized draws a plunger 16 downwardly. Said plunger is reciprocably mounted with 85 in a sleeve 17, its lower end being adapted to open and shut an opening 18 through which the chamber 13 communicates with a bleed channel 19 at such times as the plunger 16 may be raised by a spring 20 when the magnet 15 is deenergized. Said spring is interposed between the bottom wall of chamber 13 and a disk 21 which is connected to the lower end of the plunger 16 by means of a reduced neck 22. Plunger 16 carries an 90 armature 23 which reciprocates in cylinder 24. Projecting upwardly from the plunger 16 is a stem 25 which carries spaced contact bridges 26 and 27, the former of these being adapted to close a gap in a motive power 100 circuit control wire 28. The contact 27 is adapted to close a gap in a relay circuit, to

be presently referred to. For initially energizing the coil 15, the plus line wire 29 is connected thereto by a branch 30. Leading from the magnet 15 is a wire 31 which is 5 connected to one of a pair of spaced contacts 32 to provide a gap for maintaining a broken circuit under certain predetermined conditions, to be hereinafter pointed out. The other of said contacts 32 is connected by a 10 wire 33 to the minus line wire 34. A bridge contact 35 is suitably controlled to bridge the gap between contacts 32 whenever the car or train is at rest, said contact being normally held in raised position when the car 15 or train is in motion by means of a solenoid 36 which is connected at one end to ground by means of a wire 37. The other end of said solenoid is connected by a wire 38 to one of the poles 39 of a generator 40, said 20 generator being provided with a pinion 41 which meshes with a gear 42 carried by the shaft or axle 43 of the wheels 44. The other of said poles 39 is connected by a wire 45 to ground thus completing a circuit including the solenoid 36, said solenoid being thereby energized whenever the car or train 25 is in motion. A branch wire 46 leads from the wire 31 to one of a pair of spaced contacts 47 which are bridged by the contact 27 30 whenever the coil 15 is energized. The other of said contacts is connected by a wire 48 to one of a pair of spaced contacts 49. The other of these contacts is connected by a wire 50 to one of another pair of contacts 51, the other of which is connected by a wire 52 to the minus line wire 34. In the preferred embodiment of this device shown on Fig. 1, the gaps between the spaced contacts 49 and 51 are respectively closed by contact bars 53 40 and 54 which are pivoted at 55 and 56 respectively. Said contact bars as well as the pairs of contacts are preferably placed on opposite sides of the car. Each contact bar is provided with a depending arm which is 45 adapted to be engaged by any suitable instrumentality along the route of the vehicle for the purpose of bringing the train or vehicle to a standstill in the manner to be referred to.

The operation of the embodiment shown in Fig. 1 is as follows: Supposing a car or train embodying the invention be at rest. The dynamo 40 being dead, coil 36 will be deenergized and the contact 35 will rest 55 upon the contacts 32, thus closing the gap therebetween. In consequence, current will pass from plus line 29 through wire 30 to magnetic coil 15, wire 31 and wire 33 to minus line 34, the gaps between contacts 32 being then closed. Immediately coil 15 is 60 energized causing the plunger 16 to be drawn down and bringing the contacts 26 and 27 down onto the spaced contacts which form gaps in the motor circuit control wire

28 and relay circuit wires 46 and 48. This 65 brings the main line wire 28 under the control of the motorman who may thereupon set the car or train in motion. As said car or train is accelerated the dynamo 40 is energized and delivers current to the coil 36. Thereupon contact 35 is raised and breaks the connection between plus line 29 and magnet 15 by way of wire 33. The 70 energization of the magnet 15 is however maintained by way of the wire 46, contact 27, wire 48, and wire 52 to minus battery wire 34. Under these conditions, let it be supposed that some condition of traffic arises or some other reason demands that the train 75 be brought to a standstill. In the present embodiment, this will be brought about by manually or automatically causing the interposition of some instrumentality which will cause the displacement of either one or the other of the contact bars 53 and 54. 80 This breaks the circuit through magnet 15 and releases the plunger 16 which by its upward movement displaces the contacts 26 and 27 and raises the lower end of said plunger above the opening 18, thus connecting bleed passage 19 with the chamber 13 and releasing the air from chamber 5 in the 85 brake control valve. As a result, the pressure within the valve chamber 5 will fall below that in the valve chamber 4. The 90 pressure on valve 8 being thereby unbalanced causes the valve 8 to be raised against the pressure of spring 11, thus opening the train pipe 2 into the outer atmosphere through the pipe 3 and causing an automatic application of the brakes. At the same time the motor control circuit is 95 broken by the rise of contact 26 so that no current for energizing the car motor is available. It will therefore be seen that as long 100 as the car or train is in motion, the contact 26 will be held in elevated position and it will be impossible to reestablish the main control circuit 28 or to close the bleed passage 21. These parts are therefore held inoperative until the train comes to a full stop. 105

Referring now to the embodiment shown in Fig. 2, the plus line wire 29' is connected by a wire 30' with the magnetic valve within housing 14', a wire 31' leading therefrom being provided with a gap between contacts 32' between it and ground line wire 33'. The dynamo electric machine 40' which may be driven in the same manner as that referred to in the former embodiment, delivers 115 current to coil 36' which normally retains contact 35' elevated and prevents the reenergization of the magnet valve within housing 14' after the emergency has been operated and until the car comes to rest. In 120 this embodiment, the dynamo 40' delivers current to the solenoid 36' by a wire 57. Another wire 58 connects the solenoid 36' 125

to another solenoid 59 which in turn is connected by a wire 60 to a resistance coil 61 which is grounded by wire 62. A plurality of branches 63, 64, and 65 are led off from 5 different points in the coil 61 and provided with contacts 66, 67, and 68 respectively, said contacts being suitably disposed to be 10 separately engaged by a movable contact which is carried by a plunger 69, said movable contact being grounded by a wire 70. It will be seen from this description that by shifting the position of plunger 69, the resistance may be graded in such a manner as to increase or diminish the flow of current in coils 36' and 59. Simple and efficient means for imparting the desired amount of movement to the plunger 69 may be provided by mounting a roller 71 on 15 plunger 69 in suitable position to be engaged by a cam bar 72 which may constitute one of a number of said cam bars which are made of different heights to correspond with the desired amount of resistance in 20 circuit corresponding to the speed limits of 25 the zone in which the car or train may be traveling. Solenoid 59 whenever sufficiently energized, operates a plunger 73. Carried by the plunger 73 is a contact 74 which closes the gap between a pair of spaced contacts 75 whenever said plunger is in lowered position. One of said contacts 75 is grounded by wire 76. The main motive power control circuit of the car or vehicle includes a line 77 which connects with one of the spaced 30 contacts 47' between which is a gap which is normally bridged by the contact 26', and a wire 78 which connects the other of said contacts 47' with one of the contacts 75. Arranged above the contacts 75 and in 40 suitable position to be bridged by the contact 74 in its raised position, are spaced contacts 79. One of the contacts 79 is connected to a synchronizing line 81 by means of a wire 80. The other contact 79 is connected to one pole of a battery 86 by a wire 87. Leading from the synchronizing line 81 to a speed control instrumentality 83, is a wire 82. Another wire 84 connects the instrumentality 83 with minus line wire 34'. 45 Battery 86 is connected to line wire 34' by means of wire 85. Dynamo 40' is provided with a field winding 88 and a ground wire 89 which is connected thereto intermediately of the dynamo and field winding 88.

50 The operation of the embodiment shown in Fig. 2 will now be readily understood and briefly described as follows: With the car or train at rest, coil 36' is deenergized and contact 35' is lowered to close the gap between contacts 32', thus energizing the coil within housing 14' and shutting off the leakage through pipe 12' which releases the brakes in the manner pointed out in connection with the embodiment shown in Fig. 1.

At the same time contact 26' is drawn down 65 to bridge the gap between contacts 47' and inasmuch as the solenoid 59 is also deenergized, contact 74 will be in lowered position, so that the main control circuit including these parts, together with wires 77 and 78 70 will be in condition to permit the motorman to accelerate the car or train. Like in Fig. 1, contact 27' maintains the energization of the magnet in housing 14' by connecting said magnet to ground by way of wire 48' 75 and wire 52', the switch-bars 53' and 54' being normally in circuit-closing position. As the car or train becomes accelerated, coil 36 or 36' becomes energized so that the gap between contacts 32' is opened, the consequence being that the emergency brake-operating apparatus is prevented from becoming operative only by maintaining the circuit controlled by contact bars 53' and 54'. Under these conditions, the displacement of 80 either one or both of the contact bars 53' and 54' will cause an emergency application of the brakes. Supposing plunger 69 with its contact to be in lowermost position which is the case when the car or train is 85 not within a zone in which certain predetermined maximum and minimum speed limits are to be maintained, all of resistance 61 will be in circuit so that coil 59 will not be energized sufficiently to raise contact 74, the 90 character of coil 59 being such that the light current which renders coil 36' operative is not sufficient to render coil 59 operative. As the car or train enters a zone wherein maximum and minimum speed limits are to 95 be maintained, contact 69 is raised to cut out more or less or all of the resistance 61 with the result that if the speed is in excess of the maximum speed control, the dynamo 40' will generate sufficient current to render the 100 coil 59 operative and to retain it operative until the speed drops below a certain required maximum for that zone. It will be understood that when the speed of the car drops below the minimum speed, due to the 105 operation of the speed control instrumentality in casing 83, the magnetism in coil 59 will not be sufficient to retain bar contact 74 against the contacts 79. Hence the speed instrumentality 83 becomes deenergized and thus releases the car which is automatically 110 speeded up again unless retarded by the voluntary acts of the motorman. Whenever the coil 59 is thus rendered operative, it will be seen that motive power control circuit 120 will be broken without deenergizing the magnet within the housing 14', and thus without causing the emergency to operate. At the same time the contact 74 is raised, it is caused to bridge the contacts 79, thus 125 completing a circuit including battery 86, wire 87, wire 80, synchronizing line 81, wire 82, instrumentality 83 which is preferably

a brake-applying device, wire 84, minus line wire 84', and wire 85 to battery. This causes an application of the brakes until the speed drops below the maximum speed limit at 5 which time the current supplied by dynamo 40' has become insufficient to enable the solenoid 59 to hold the plunger 73 in raised position. Thereupon the brakes are released and the motive power control circuit 10 is reestablished without bringing the car or train to rest as would be the case should the emergency apparatus become operative.

Obviously, various changes could be made in the arrangement of circuits and in the 15 constructions of the several instrumentalities employed without departing from the broad spirit of my invention which resides in the combinations of elements set forth in the appended claims.

20 I claim:

1. In a vehicle, the combination of speed control means adapted to prevent the speed of said vehicle rising above a predetermined maximum or falling below a predetermined 25 minimum, an operating circuit for said speed control means, emergency means of relatively higher power than said speed control means, for bringing said vehicle to rest, an operating circuit for said emergency 30 means, and means depending upon the movement of said vehicle for co-operatively controlling said operating circuits.

2. In a vehicle, the combination of speed control means adapted to prevent the speed 35 of said vehicle rising above a predetermined maximum or falling below a predetermined minimum, emergency means for bringing said vehicle to rest, an operating circuit for said emergency means, another circuit for 40 operating said speed control means independently of said emergency means, and means depending upon the movement of said vehicle for co-operatively controlling the operation of said speed control means 45 and said emergency stopping means.

3. In a vehicle, the combination of speed control means adapted to prevent the speed of said vehicle rising above a predetermined maximum or falling below a predetermined 50 minimum, emergency means for bringing said vehicle to rest, operating circuits for said emergency means and said speed control means respectively, and means depending upon the movement of said vehicle for 55 controlling said operating circuits.

4. The combination with a vehicle, of braking mechanism therefor, a control circuit for said braking mechanism, a relay in said control circuit, a circuit breaker also 60 in said control circuit, means depending upon the movement of the vehicle for operating said circuit breaker, a relay circuit controlled by said relay, a circuit breaker

other than said relay for said relay circuit, and a main operating circuit for said vehicle 65 controlled by said relay.

5. The combination with a vehicle, of an emergency air-release valve for applying brakes on said vehicle, an emergency magnet valve for controlling said air-release 70 valve, a circuit for controlling said magnet valve, said control circuit being provided with a circuit breaker controlled by the movement of said vehicle, a branch line leading from said control circuit and excluding said circuit breaker, said branch line being provided with a circuit breaker operated by said magnet valve, and automatic means operable from without the vehicle for breaking the branch line circuit. 75

6. The combination with a vehicle, of an emergency air-release valve for applying brakes on said vehicle, an emergency magnet valve for controlling said air-release 80 valve, a circuit for controlling said magnet valve, said control circuit being provided with a circuit breaker controlled by the movement of said vehicle, a branch line leading from said control circuit and excluding said circuit breaker, said branch line being provided with a circuit breaker operated by said magnet valve, and automatic means operable from without the vehicle for breaking the branch line circuit, 90 said magnet valve being provided with an air chamber connected to said emergency air-brake valve.

7. The combination with a vehicle, of an emergency air-release valve for applying brakes on said vehicle, an emergency magnet valve for controlling said air-release 100 valve, a circuit for controlling said magnet valve, said control circuit being provided with a circuit breaker controlled by the movement of said vehicle, a branch line 105 leading from said control circuit and excluding said circuit breaker, said branch line being provided with a circuit breaker operated by said magnet valve, and automatic means operable from without the 110 vehicle for breaking the branch line circuit, and a main operating circuit for said vehicle having a circuit breaker operable by said magnet valve.

8. In a vehicle, the combination with an 115 instrumentality for automatically controlling the application of brakes, said instrumentality being adapted when energized to prevent the application of brakes, of an electric circuit for initially energizing said 120 instrumentality, said circuit being provided with a circuit breaker normally retained in open position by the movement of the vehicle, and a relay circuit for maintaining the energization of said instrumentality, 125 said relay circuit embodying a circuit

- breaker normally retained in closed position by the energization of said instrumentality and a second circuit breaker adapted to be operated automatically at predetermined 5 points along the route of said vehicle.
9. In a vehicle, automatic apparatus for controlling the speed of said vehicle without bringing it to rest, automatic emergency apparatus for bringing said vehicle to rest, 10 and means depending upon the movement of said vehicle for rendering said speed control apparatus and said emergency apparatus operative, said means including an electric generator suitably connected to deliver power to said means only when the vehicle is in motion.
10. In a vehicle, automatic apparatus for controlling the speed of said vehicle without bringing it to rest, automatic emergency 20 apparatus for bringing said vehicle to rest, and means depending upon the movement of said vehicle for rendering said speed control apparatus and said emergency apparatus operative, said means including a 25 dynamo connected with the running gear of the vehicle.
11. In a vehicle, the combination of speed control means adapted to prevent the speed of said vehicle rising above a predetermined maximum or falling below a predetermined 30 minimum, an operating circuit for said speed control means emergency means for bringing said vehicle to rest, an operating circuit for said emergency means, said emergency 35 means being automatically retained in operation until the vehicle is at rest, and means depending upon the movement of said vehicle for controlling the operating circuits for said speed control means and said emergency stopping means.
12. In a vehicle, the combination of speed control means adapted to prevent the speed of said vehicle rising above a predetermined maximum or falling below a predetermined 45 minimum, emergency means for bringing said vehicle to rest, said emergency means being automatically retained in operation until the vehicle is at rest, and means depending upon the movement of said vehicle 50 for controlling the operation of said speed control means and said emergency stopping means, and including instrumentalities for operating said emergency stopping means and speed control means together and one of said means independently of the other.
13. In a system of operating railway cars, the combination with a car, of emergency means adapted when operated to bring the car to rest, an energizing circuit for said 60 emergency means provided with a circuit breaker adapted to be automatically operated by said emergency means to maintain a break in said circuit, and another circuit for energizing said emergency means, including a normally open switch which is 65 moved into closed position only when the car is at rest.
14. In a car, the combination of an emergency device adapted when actuated to bring said car to rest, a speed control instrumentality for maintaining predetermined maximum and minimum speed limits, an electro-responsive device for controlling the operation of said emergency device, an electro-responsive device for controlling the operation of said speed control instrumentality, and a dynamo driven by the running gear 75 of said car and having circuit connections with said electro-responsive devices.
15. In a car, the combination of an emergency device adapted when actuated to bring said car to rest, a speed control instrumentality for maintaining predetermined maximum and minimum speed limits, an electro-responsive device for controlling the operation of said emergency device, an electro-responsive device for controlling the operation of said speed control instrumentality, and a dynamo driven by the running gear of said car and having circuit connections with 80 said electro-responsive devices, said electro-responsive devices being connected up in series with said dynamo.
16. In a car, the combination of an emergency device adapted when actuated to bring 95 said car to rest, a speed control instrumentality for maintaining predetermined maximum and minimum speed limits, an electro-responsive device for controlling the operation of said emergency device, an electro-responsive device for controlling the operation of said speed control instrumentality, and a dynamo driven by the running gear of said car and having circuit connections with 105 said electro-responsive devices, said electro-responsive devices being connected up in series with said dynamo, and one of said devices being operative at relatively low power in comparison to the other.
17. In a car, the combination of an emergency device adapted when actuated to bring said car to rest, a speed control instrumentality for maintaining predetermined maximum and minimum speed limits, an electro-responsive device for controlling the operation of said emergency device, an electro-responsive device for controlling the operation of said speed control instrumentality, and a dynamo driven by the running gear of said car and having circuit connections 110 with said electro-responsive devices, said electro-responsive device for controlling the emergency devices being operable at relatively low power compared to the electro-responsive device for controlling said speed 120 control instrumentality.

18. In a car, an emergency device adapted when operated to bring said car to rest, a solenoid for resetting said device, a speed control instrumentality for maintaining predetermined maximum and minimum speed limits, a solenoid for controlling the operation of said instrumentality, and a dynamo adapted to generate power only when the car is in motion, said dynamo having circuit connections with both of said solenoids. 65
19. In a car, an emergency device adapted when operated to bring said car to rest, a solenoid for resetting said device, a speed control instrumentality for maintaining predetermined maximum and minimum speed limits, a solenoid for controlling the operation of said instrumentality, a dynamo adapted to generate power only when the car is in motion, said dynamo having circuit connections with both of said solenoids, and a motive power control circuit embodying a circuit breaker which is operably connected to said second mentioned solenoid. 70 75
20. In a car, an emergency device adapted when operated to bring said car to rest, a solenoid for resetting said device, a speed control instrumentality for maintaining predetermined maximum and minimum speed limits, a solenoid for controlling the operation of said instrumentality, a dynamo adapted to generate power only when the car is in motion, said dynamo having circuit connections with both of said solenoids, a variable resistance in circuit with said speed control solenoid, and means depending upon the motion of said car for varying said resistance. 80
21. In a car, an emergency device adapted when operated to bring said car to rest, a solenoid for resetting said device, a speed control instrumentality for maintaining predetermined maximum and minimum speed limits, a solenoid for controlling the operation of said instrumentality, a dynamo adapted to generate power only when the car is in motion, said dynamo having circuit connections with both of said solenoids in series, and means for automatically varying the resistance of said circuit, said speed control solenoid being operable only when there are predetermined amounts of resistance in circuit and said emergency solenoid being operable under any amount of resistance that can be introduced into the circuit. 85 90 95
22. In a car, a speed control instrumentality, an energizing circuit therefor, embodying spaced contacts, a motive power control circuit embodying spaced contacts, a bridge contact adapted to alternately bridge the gaps in said circuits, an electro-responsive device for moving said bridge contact, and a source of power for energizing said solenoid, said source varying in power to correspond with the speed of the car. 100
23. In a car, a speed control instrumentality, an energizing circuit therefor embodying spaced contacts, a motive power control circuit also embodying spaced contacts, a bridge contact normally bridging the spaced contacts in said motive power control circuit, an electro-responsive device for moving said bridge contact therefrom and into position to bridge the contacts in said speed control energizing circuit, a source of energy for energizing said solenoid, and means for varying the resistance in circuit with said solenoid and source of power, said solenoid being capable of energization only when the resistance in circuit is below a predetermined amount. 105 110 115
24. In a car, a speed control instrumentality, an energizing circuit therefor embodying spaced contacts, a motive power control circuit also embodying spaced contacts, a bridge contact normally bridging the spaced contacts in said motive power control circuit, an electro-responsive device for moving said bridge contact therefrom and into position to bridge the contacts in said speed control energizing circuit, a source of energy for energizing said solenoid, and means for varying the resistance in circuit with said solenoid and source of power, said solenoid being capable of energization only when the resistance in circuit is below a predetermined amount, said resistance varying means being dependent for its operation on the motion of the car. 120
25. In a car, the combination of a speed control instrumentality, a battery having one pole connected thereto, a pair of spaced contacts connected respectively to said instrumentality and the other pole of said battery, a bridge contact adapted to bridge said contacts, means depending on the movement of said car for holding said bridge contact out of engagement with said spaced contacts, and a motive power control circuit embodying spaced contacts suitably disposed to be bridged by said bridge contact when held away from the first said contacts. 125
26. In a train of cars, a synchronizing line extending from one car to another, a speed control instrumentality on each car, 110 a source of energy, a circuit on each car including said source of energy, said synchronizing line, and said speed control instrumentality, said circuit including spaced contacts, a motive power control circuit embodying spaced contacts on each car adjacent to the first mentioned contacts, a bridge contact normally bridging the motive power circuit contacts, and means depending on the speed of said car for moving said bridge contact into position to bridge the first said contact. 120 125

contacts, said bridge contact on each car being adapted by said synchronizing line to complete the energizing circuit for every speed control instrumentality in the train.

27. In a vehicle, the combination of speed control means adapted to prevent the speed of said vehicle rising above a predetermined maximum or falling below a predetermined minimum, emergency means for bringing said vehicle to rest, operating circuits for

said emergency means and said speed control means respectively, and means depending upon the movement of said vehicle for controlling said operating circuits, said emergency stopping means being operative 15 independently of said speed control means.
